J. W. Webb,
Door Scanner.
N° 10,511. Patented Feb. 7, 1854.

UNITED STATES PATENT OFFICE.

JOSEPH W. WEBB, OF WASHINGTON, DISTRICT OF COLUMBIA.

PORTABLE DOOR-LOCK.

Specification of Letters Patent No. 10,511, dated February 7, 1854.

To all whom it may concern:

Be it known that I, JOSEPH W. WEBB, of Washington, in the District of Columbia, have invented a new and useful portable door-lock, the same being an improvement on the portable door-lock for which a patent was granted to Samuel P. Kittle on the 7th day of June, A. D. 1853, and which is particularly adapted to the use of persons traveling, to be used on the doors of lodging-rooms when there are no locks or bolts or where they are deemed insufficient for securing the occupant against the intrusion of thieves and burglars; and I do hereby declare that the following is a full, clear, and exact description of the construction and operation of the same, reference being had to the annexed drawings, making a part of this specification, in which like letters represent corresponding parts.

A is an iron bar about two inches in length, one inch and a quarter wide by one eighth of an inch thick, out of the forward end of which a piece is cut between its outer edges sufficient to leave two pieces extending from the main part of the bar about a quarter of an inch in width. These pieces are then filed to a feather edge and turned up about a quarter of an inch in height, as represented at b, in such manner as to form with the inner face of the main bar A an angle of about one half of forty five degrees, so that the points or edges of the claws will form a considerable inclination toward the rear end of said bar, the object of such inclination being for the purpose of more effectually driving said claws into the casing of the door upon pressure being applied on the outside of the door to force it open, the effect of such pressure being to more firmly drive the claws into the casing. In both edges of the bar at c, small notches are cut, into which the thumb piece B drops when run upon the bar. The notches c are cut in both edges of the bar A, so that my lock can be used on doors which open either to the right or left.

The thumb piece B is made of iron, and is a bar about two and a half inches long, with both ends turned up rounding, and has a longitudinal opening d through it, suffi-

cient in width and length to admit of its being run upon the bar A. This thumb piece is self adjusting, and when run upon the bar A drops down, as may be desired, 55 into either one of the notches c, thus forming a secure lock with the bar. Said thumb-piece is also of sufficient width to lap over a portion of the door and the door casing each side of the crack between the door and 60 its casing in which the bar A is to be placed. It sometimes happens that the crack between the door and its casing, owing to the shrinking of the wood, is so wide that the claws b are not sufficiently pressed into the 65 casing by the closing of the door. In such case I use a crack piece E of the same material and width as the bar A and about three fourths of an inch long, with one end a quarter of an inch thick and tapering 70 down to an edge at its other end. This piece has a pintle f on its face side to fit the hole g in the bar A when it is used, and being tapering on the side opposite its face side door short of using violent means to effect 75 upon it.

The operation of using the lock is as follows: The bar A is placed with its claws b against that part of the door-casing which corresponds with the edge of the door when 80 closed. The claws are slightly driven into the wood by pressure of the hand upon the bar A. The door being then closed, forces the claws firmly into the casing. The thumb piece B is then run upon the bar, drops 85 down into one of the notches c closest to the door, and the operator finds the door effectually locked against all persons on the outside of the room, and without the possibility of "picking" the lock or opening the 90 door short of using violent means to effect an entrance.

What I claim as my invention and desire to secure by Letters Patent is—

The claws b in combination with the bar 95 A and thumb piece B, constructed in the manner and for the purpose herein described.

JOSEPH W. WEBB.
